VISE FOR TYPOGRAPHICAL MACHINES

Allie Horace Kelley, Jr., Memphis, Tenn., assignor
to Intertype Corporation, Brooklyn, N. Y., a
corporation of New York

Application December 13, 1937, Serial No. 179,523

13 Claims. (Cl. 199—50)

The present invention relates to improvements in typographical machines and more especially to those of the general class disclosed in U. S. Letters Patent No. 436,532 granted September 5 16, 1890, wherein character bearing matrices are assembled from suitable magazines or storage receptacles into composed lines and the lines then clamped endwise between a pair of opposed confining jaws for presentation to a slotted mold in 10 which the type bars or slugs are cast, after which the matrix lines are removed from between the jaws to permit the matrices to be returned to their proper places of storage.

In practice, machines of this class are called 15 upon to produce type slugs of different lengths according to the width of the page or column to be printed therefrom. The mold slot in which the slugs are cast is accordingly made variable in length, and the line confining jaws, com- 20 monly known as vise jaws, between which the line is clamped endwise during the casting operation, are made correspondingly adjustable. Moreover, modern machines of this class are frequently equipped with devices arranged for cou- 25 pling one or both jaws for automatic movement of either or both jaws from their open or line receiving position in order to quad or center lines of less length than the length of the mold slot in front of which they are presented, an example of 30 such devices being disclosed in U. S. Letters Patent No. 1,970,527 granted August 14, 1934.

In machines of this class, as well known, both vise jaws are freely slideable in the so-called "vise" 35 of the machine, and the right hand jaw normally occupies a fixed open or line receiving position where its outer end banks against a stationary stop. The left hand jaw, however, according to the usual construction of machines of this class, banks at its outer end against a stop or block 40 which is independent of the jaw and is adjustable in order to fix the initial operative position of this jaw to correspond with the line measure or length of slug it is desired to cast, and a locking device is provided to retain such stop at the 45 selected line measure setting. When the left hand jaw stop is unlocked and adjusted inwardly, as when reducing the normal opening between the two jaws, the left hand jaw moves inwardly with the stop. However, when the stop 50 is adjusted outwardly to increase the normal space or opening between the jaws to accommodate a longer matrix line between them, the left hand jaw does not move outwardly with such stop but instead remains standing at the shorter 55 line measure position and must be pushed back

manually against the stop before a longer line can be introduced between the jaws.

The primary object of the present invention is to provide a simple and effective construction which will avoid the necessity for such manual 5 operation and which at the same time will be adaptable to machines equipped for quadding and centering movement of the vise jaws away from their stops. The invention accordingly provides means for connecting the left hand vise 10 jaw to its adjustable stop in such a manner that both of these parts remain in intimate contact and move as a single unit when the stop is adjusted in either direction, that is, toward the right hand jaw as for decreasing, or away from 15 the right hand jaw for increasing the distance between the jaws. Such connecting means however, according to the present invention, is of such a nature that the left hand jaw will instantly and automatically become released from 20 its stop whenever this jaw is used for quadding or centering a line, and will become reconnected to the stop upon being returned, as by the quadding mechanism, to normal or open position 25 against the stop.

More particularly, the invention provides a connection between the left hand vise jaw and its adjustable stop which is operable or inoperable whenever required, so that this jaw, while normally retained against its stop for movement 30 as a unit therewith in either direction for adjusting purposes, is free to move independently of its stop for quadding or centering purposes.

A further object of the invention is to provide means actuated by the jaw adjusting devices and 35 operative to temporarily or momentarily break or disconnect the coupling between the left hand jaw and such devices as may be present in the machine for imparting quadding or centering movement of such jaw.

To these and other ends, the invention consists in certain improvements and combinations and arrangements of parts all as will be hereinafter more fully described, the features of novelty 45 being pointed out more particularly in the claims 40 at the end of this specification.

In the accompanying drawings:

Fig. 1 is a top plan view of the usual vise of a machine of the class hereinbefore referred to, 50 showing the vise jaws and other associated parts and portions of a quadding device and certain of the devices provided according to the present invention;

Fig. 2 is an elevation of the structure shown 55

in Fig. 1 as viewed from the left hand end thereof;

Fig. 3 is a front elevation of the left hand portion of the structure shown in Fig. 1;

5 Fig. 4 is a view similar to Fig. 2 but shows the parts in a different operative position in accordance with the present invention;

Fig. 5 is a top plan view of the left hand portion of Fig. 1, with portions broken away to show 10 details of the mechanism for adjusting the left hand vise jaw and its stop and of the coupling device for effecting quadding or centering movement of this jaw;

Fig. 6 is a vertical section taken on the line 15 6—6 in Fig. 1 and showing the connection provided by the present invention between the left hand vise jaw and its adjustable stop; and

Fig. 7 is a front elevation of the right hand end of the vise shown in Fig. 1.

20 Similar parts are designated by the same reference characters in the several figures.

The preferred embodiment of the invention is shown in the present instance as applied to a line casting machine of the general class hereinbefore referred to, but it is to be understood that the invention is not restricted to the precise construction shown since equivalent constructions are contemplated and such will be included within the scope of the claims.

30 In the accompanying drawings, 1 represents the usual so-called "vise" in which right hand and left hand vise jaws 2 and 3 respectively are supported on suitable blocks or plates 4 and 5, the latter being freely slidable in a longitudinal 35 channel 1^a in the vise. The right hand jaw 2 is shown in Fig. 1 in the normal or constant line receiving position it occupies regardless of the length of the matrix lines from which the casts are being made, this jaw when in such position 40 banking against the usual fixed stop. The left hand jaw 3, as usual, may be set in different desired line measure positions, it ordinarily banking for such purpose against an adjustable stop. The construction and mode of operation of such 45 stop may be varied to suit different conditions, but the stop shown in the present instance is substantially the same as that shown and described fully in U. S. Letters Patent No. 1,108,758 granted August 25, 1914, to which reference may be had

50 for a detailed disclosure thereof. For the purpose of the present invention, such stop may be described briefly as comprising a rotatable adjusting knob 6 fixed to a shaft 7, the latter being journaled in the vise to rotate and also slide forwardly and rearwardly therein, and the inner end

55 of this shaft has a pinion 8 fixed thereon which is rotatable with the knob 6 and shaft 7. A sleeve 9 is fitted in the vise and in this sleeve is mounted a bar 10 which is slidable longitudinally 60 in a bearing 11 in the vise, the bar 10 having teeth 12 on its underside which cooperates with the pinion 8 and having serrations 13 along its forward side to cooperate with a locking slide 14, the latter being reciprocable forwardly and rearwardly in the vise, with the knob 6, as in said 65 Patent No. 1,108,758, but cooperating with the knob to effect such sliding movement in a somewhat different manner, as will hereinafter appear. The left hand jaw stop 15 is secured to

70 the inner end of the bar 10, this stop cooperating with a lug or abutment 16 which is fixed to the underside of the block or plate 5 supporting the left hand jaw 3.

Ordinarily, in machines having an adjustable stop such as that shown in Patent No. 1,108,758,

the lug 16 merely banks against the jaw stop 15 to determine the line measure setting of the left hand jaw 3. Upon release of the locking slide 14 from the bar 10 and subsequent rotation of the adjusting knob 6 in a clockwise direction, the jaw 3 will be influenced by the resulting inward movement of the stop 15 toward the right and against the lug 16 and will be thus moved to the right in Fig. 6. If, however, the stop 15 is moved outwardly or toward the left in that figure, as by 10 anti-clockwise rotation of the adjusting knob 6, it will be obvious that, in the absence of a connection between the lug 16 and the stop 15, the jaw 3 would not move outwardly with the stop, thus requiring manual sliding of the adjustable or left hand jaw 3 outwardly to bring the lug 16 thereon against the stop in its newly adjusted position.

The present invention overcomes the necessity for such manual sliding of the left hand vise jaw when it stops is adjusted outwardly as for wider or longer line measures. The invention accordingly provides between the left hand jaw 3 or suitable parts associated therewith and the adjustable stop 15 a connection which enables the jaw and its stop to move as a unit when adjustments are made in either direction inwardly or outwardly and is also capable of permitting the jaw instantly and automatically to become released from its stop and to move inwardly independently of the stop for quadding or centering 30 purposes and to reconnect with the stop each time it is returned to open position by the quadding or centering mechanism.

Preferably and as shown in the present instance, this connection comprises a depression 17 provided in a part associated with the adjustable jaw 3, it being preferably provided in the underside of the supporting block 5 thereof as shown in Fig. 6, and a ball 18 located and confined in a vertical bore 19 in the stop 15 near its inner end, the ball being adapted to protrude slightly beyond the upper surface of the stop and being pressed upwardly by a spring 20 which is retained in the bore 19 by a screw 21. The ball 18 and depression 17 are so located that they will register when the lug 16 abuts against the stop 15, the depression 17 providing a seat to receive the ball and in which the ball will be retained yieldingly by the spring 20.

The depression 17 and ball 18 thus constitute 50 means for connecting the left hand or adjustable jaw 3 to its stop in such a manner that this jaw and its stop will move as a unit when the stop is adjusted in either direction, inwardly or outwardly. Moreover, since the ball is pressed yieldingly into the depression, the connection between the adjustable jaw and its stop will readily release if the jaw is urged inwardly while the locking slide 14 is engaged, as it normally is, with the bar 10. Such release of the connection between the adjustable or left hand jaw and its stop will occur when the left hand jaw is coupled to and actuated by quadding or centering mechanism such for example as that shown in the accompanying drawings and described in detail in 60 Patent No. 1,970,527 hereinbefore referred to.

Such quadding or centering mechanism, insofar as it concerns the present invention, may be described briefly as comprising a rack bar 22 releasably connected, as disclosed for example in 70 Patent No. 1,970,527, to the right hand jaw 2, a similar rack bar 23 rigidly connected to the left hand jaw 3, a pinion 24 on a vertically reciprocable spindle 25 and movable into and out of mesh with the rack bars 22 and 23 to couple and 75

uncouple them, and a power operated jaw closing lever 26 connected by a link 27 to the rack bar 22 and operative as disclosed in said patent. A control knob or handle 28 is also provided which 5 is fixed to one end of a rock shaft 29 mounted in the vise and extending across the same, the shaft 29 having means for connecting it to the pinion shaft 25 so that by setting the knob or handle 28 to the desired position, one or both of 10 the vise jaws will be so coupled to the jaw closing lever 26 as to be moved inwardly away from the respective stops which determine their full line measure positions. As shown for example, a crank arm 30 is fixed to the shaft 29 and has a stud 15 31 fixed to and projecting from a side thereof, and a stud 32 which is fixed on the housing 33 for the pinion shaft or spindle 25 pivotally supports a lever 34. One end of this lever has a pin 35 fixed thereto to project laterally therefrom into 20 a circumferential groove in the pinion shaft 25, and the other end of the lever 34 is provided with a cam surface 36 which is engageable by the stud 31 on the arm 30. The purpose of this mechanism 25 is to raise and lower the pinion 24 to couple 25 the left hand jaw 3 to the quadding mechanism for quadding or centering movement thereby and to uncouple this jaw from the quadding mechanism. When the pinion is lowered into mesh with both rack bars 22 and 23, as shown in Fig. 6, 30 corresponding with the position of the parts shown in Figs. 2 and 5, the vise jaws 2 and 3 connected to the respective rack bars will move simultaneously and equidistantly, one toward the other, to effect a matrix line centering operation 35 when the quadding or centering mechanism operates, the lever 26 being operated at the proper time and acting on the rack bar 22 to move the latter and the right hand jaw 2 toward the left and to rotate the pinion 24 and thereby move the 40 rack bar 23 and the left hand jaw 3 toward the right. While the pinion 24 is in raised position, at which time the parts occupy the position shown in Fig. 4, the lever 26, when actuated, will act on the rack bar 22 to move the right hand jaw only, thus performing a flush left quadding operation. 45 While the pinion 24 is in its lowered position in mesh with both rack bars 22 and 23 and the rack bar 22 is detached from the right hand jaw 2, as by the releasing device disclosed in Patent No. 50 1,970,527, the bar 22, upon actuation of the lever 26, will move to the left without moving the right hand jaw 2 with it but the pinion 24 meshing with the rack bar 22 will be rotated and will move the rack bar 23 to the right, so that the left hand jaw 55 3 alone will be moved to perform a flush right quadding operation. The different positions of the knob or handle 28 for thus controlling these operations of the quadding or centering mechanism are indicated on the dial 128 in Fig. 7.

60 Since the rack bar 23 is rigidly secured to the left hand jaw 3 or its associated support 5, this jaw cannot be adjusted to different initial positions except while the pinion 24 is disengaged from the rack bar 23. The present invention accordingly provides means for temporarily or momentarily uncoupling the left hand jaw and the quadding or centering mechanism, and such means is preferably actuated automatically by the left hand jaw adjusting means. In the embodiment of the invention herein shown, means 65 is provided which is actuated by the left hand jaw adjusting means and is operative to temporarily or momentarily break any coupling that may exist between the pinion 24 and the left hand 70 vise jaw, thus freeing this jaw for adjusting pur-

poses and to subsequently recouple this jaw to the pinion 24 for quadding or centering purposes. The means provided for this purpose, as shown in the present instance, comprises a lever 37 which is fulcrumed on a stud 38 fixed in a bearing block 5 39, the latter being fixed on the vise, the lever 37 carrying toward its lower end a pin 40 which projects laterally therefrom and overlies the flange 6^a of the left hand jaw adjusting knob 6. The lever 37 extends upwardly from its fulcrum 10 38, as shown in Figs. 2, 3 and 4, and its upper end is located to contact with a pin 41 which is fixed to and projects laterally from the crank arm 30. A spring 42 is attached to the lower end 15 of the lever 37, the other end of this spring being attached to a suitable part of the vise. This spring acts to retain the pin 40 near the lower end of the lever 37 against the flange 6^a and, acting through this flange and the shaft 7, to retain the locking slide 14 and the knob 6 in their inner or 20 rear position with the slide 14 in locking engagement with the bar 10.

With this arrangement, by pulling the jaw adjusting knob 6 forwardly, its flange 6^a, engaging the pin 40, will rock the lever 37 about its fulcrum 38. Should the crank arm 30 at this time occupy the position shown in Fig. 2 in which position the pinion 24 is engaged with the rack bar 23 connected to the left hand jaw 3 and the latter therefore coupled to the pinion for quadding 30 or centering purposes, such rocking motion of the lever 37 will bring its upper end into contact with the pin 41 on the crank arm 30 and will thereby swing the latter and the shaft 7 about the latter as an axis. The stud 31 on the crank 35 arm 30 will be thereby moved through an arc which intersects the projection 36^a on the cam surface 36 on the lever 34, thus rocking the latter which in turn, through the pin 35 thereon, will raise the spindle 25, the parts being thereby 40 brought into the position shown in Fig. 4. The pinion 24 will then be uncoupled from the rack bar 23 and the jaw 3 and while the knob 6 is held forwardly against the tension of the spring 42, the left hand jaw 3 and its stop 15 may be 45 adjusted along the vise in either direction inwardly or outwardly by rotation of the knob 6. Upon completion of such adjustment, the spring 42 will return the knob 6 inwardly when released by the operator, and at the same time said spring 50 will rock the lever 37 in a direction to swing its upper end back to the position shown in Fig. 2, the arm 30 however remaining in the position shown in Fig. 4 by the cam surface 36 until the control knob or handle 28 is again rotated to the 55 center position if desired for centering or to flush right position if quadding with the left hand jaw only is desired, it being noted that the cam surface 36 on the lever 34 is of such shape as to cause the pinion 24 to occupy its lowered position 60 in coupled relation with the rack bar 23 when the control knob or handle 28 occupies either the center position for centering matrix lines or its flush right position for quadding with the left hand jaw only, and when the control knob or handle 28 is 65 set in the flush left position the pinion 24 will be in its raised position and uncoupled from the rack bar 23 for quadding with the right hand jaw only.

Means is provided for retaining the locking 70 slide 14 in locking relation with the bar 10 until the pinion 24 is fully raised and uncoupled from the rack bar 23. For this purpose, the locking slide 14 is provided with a forwardly extending hook-like extension 14^a which extends around 75

the lower portion of the lever 37, this extension having opposed surfaces 43 and 44 thereon between which the lever 37 operates with a clearance. This clearance permits the lever 37 to be 5 rocked forwardly sufficiently by forward movement of the knob 6 to uncouple the pinion 24 from the rack bar 23 before the locking slide 14 is retracted from the bar 10 to unlock it, which occurs when the lever 37 contacts with the surface 43 on the extension 14a. When the lever 37 10 is rocked in the opposite direction under the action of the spring 42, it contacts with the other surface 44 on the extension 14a and thereby returns the locking slide 14 to locking position.

15 I claim as my invention:

1. In a typographical machine having a matrix line confining jaw provided with means for adjusting it inwardly for lines of different lengths, and means for moving such jaw inwardly away
20 from the adjusting means for quadding or centering lines, means for connecting said jaw to its adjusting means for movement outwardly therewith, said connecting means being releasable upon actuation of the jaw by the quadding and centering means.

2. In a typographical machine having a matrix line confining jaw, adjusting means operable at will to move said jaw inwardly to different line receiving positions, and quadding means operative to move such jaw inwardly from its line receiving position, means operative to connect said jaw to said adjusting means to move said jaw outwardly thereby and to disconnect said jaw from said adjusting means when the jaw is operated by the quadding means.

3. In a typographical machine having a matrix line confining jaw, adjusting means operable at will to move said jaw inwardly and set it at different line receiving positions, and quadding means operative to move such jaw inwardly away from the adjusting means, a yieldable connection between said jaw and adjusting means operable to retain the latter and said jaw in connected relation for simultaneous outward movement but permitting inward movement of the jaw alone under the influence of said quadding means.

4. In a typographical machine having a movable matrix line confining jaw, adjusting means operable at will to set said jaw to confine lines of different lengths, and quadding means having means for connecting it to said jaw to move it into different positions for quadding or centering lines, means for connecting said jaw to said adjusting means for movement thereby and also independently thereof, and means operative automatically by the operation of the adjusting means for disconnecting said jaw from the quadding means.

60 5. In a typographical machine having a movable matrix line confining jaw, adjusting means operable at will to set said jaw to confine lines of different lengths, releasable means for holding said adjusting means in different adjusted positions, quadding means, and a connection for coupling and uncoupling the quadding means with respect to said jaw, means for connecting said jaw to said adjusting means for adjustment thereby and for movement by the quadding means independently thereof, and means operative when said holding means is released to uncouple said jaw from the quadding means.

65

70

6. In a typographical machine having a movable matrix line confining jaw, adjusting means operable at will to set said jaw to confine lines of

different lengths, means releasable by said adjusting means and adapted to hold the latter in different set positions, quadding means, and a connection for coupling and uncoupling the quadding means with respect to said jaw, means connecting said jaw to said adjusting means for adjustment thereby and also permitting independent movement thereof, and means operative to uncouple said jaw from the quadding means when said holding means is released. 10

7. In a typographical machine having a movable matrix line confining jaw, adjusting means operable at will to set said jaw to confine lines of different lengths, means for releasably holding the adjusting means in different adjusted positions corresponding with different set positions of said jaw, quadding means, and a connection for coupling and uncoupling the quadding means with respect to said jaw, means yieldably connecting said jaw to said adjusting means for movement inwardly and outwardly thereby and permitting independent inward movement thereof, and means operative to uncouple said jaw from the quadding means when said holding means is released. 10

8. In a typographical machine having a movable matrix line confining jaw, adjusting means operable to set said jaw in different positions to confine lines of different lengths, means releasable by said adjusting means and adapted to hold the latter in different adjustments for different set positions of the jaw, quadding means, and a connection for coupling said quadding means to and uncoupling it from said jaw, means normally retaining said jaw connected to said adjusting means for concurrent adjustment inwardly and outwardly therewith and also permitting independent movement of said jaw by the quadding means, and means actuated upon the release of said holding means for automatically uncoupling said jaw from the quadding means. 40

9. In a typographical machine having a movable matrix line confining jaw, adjusting means operable to set said jaw in different positions to confine lines of different lengths, means releasable by said adjusting means and adapted to hold the latter in different adjustments for different set positions of the jaw, quadding means, and a connection for coupling said quadding means to and uncoupling it from said jaw, means for connecting said jaw to said adjusting means for adjustment as a unit therewith and also permitting independent movement of said jaw, and means actuated by the movement of said holding means for uncoupling said jaw from the quadding means after said holding means has been released and for coupling said jaw to the quadding means when the holding means is restored to holding condition.

10. In a typographical machine having a movable matrix line confining jaw having a rack bar connected thereto, adjusting means operable manually to set said jaw in different positions to confine lines of different line measures, a locking member releasable by operation of said adjusting means and adapted to hold the latter in different adjustments for different set positions of said jaw, quadding means, and a pinion operable by the quadding means and movable into and out of engagement with said rack bar, means normally retaining said jaw connected to said adjusting means for adjustment concurrently therewith but releasable to permit movement of said jaw by the quadding means independently of the adjusting means and a connection between said

locking member and pinion operative to automatically disengage the latter from said rack bar prior to release of said locking member.

11. In a typographical machine having a matrix line confining jaw, and a stop adjustable at will and operable to move said jaw inwardly and to set it at different line receiving positions, a ball and socket connection between said stop and jaw operable to connect them for movement of the jaw inwardly and outwardly as a unit with said stop and yieldable to permit inward movement of the jaw independently of the stop.

12. In or for a typographical machine having a line confining jaw, jaw adjusting means and quadding means for operating the jaw independently of said adjusting means, and means operative normally to retain the jaw and adjust-

ing means in connected relation for simultaneous movement inwardly and outwardly as a unit but to permit independent inward and outward movement of the jaw by the quadding means.

13. In a typographical machine having a matrix line confining jaw, manually operable adjusting means therefor and quadding means for actuating the jaw to move it inwardly and outwardly relative to said adjusting means, connecting means between said jaw and adjusting means adapted to enable movement of the jaw in either of two directions by the adjusting means but self-releasing to permit independent movement of the jaw when the latter is actuated by the quadding means. 5 10 15
